UNITED STATES PATENT OFFICE.

EDWARD H. MOYLE, OF LOS ANGELES, CALIFORNIA.

DESIGN FOR A STAMP-MILL FRAME.

44,575.

Specification for Design.

Patented Aug. 26, 1913.

Application filed June 19, 1913. Serial No. 774,694. Term of patent 14 years.

To all whom it may concern:

Be it known that I, EDWARD H. MOYLE, a citizen of the United States, residing at Los Angeles, in the county of Los Angeles and State of California, have invented a new, original, and ornamental Design for a Stamp-Mill Frame, of which the following is a specification, reference being had to the accompanying drawing, forming part thereof.

Figure 1, is a front elevation and Fig. 2, is a perspective view of a mill frame, showing my new design.

I claim:

The ornamental design for a stamp mill frame, as shown.

EDWARD H. MOYLE.

Witnesses:

N. L. PERRY,
F. GAIL EWING.
